UNITED STATES PATENT OFFICE

2,616,574

DEVICE FOR SEPARATING SHEETLIKE MATERIALS

Erik Johanson, Bertil Bergvall, and Uno Alfredsson, Jonkoping, Sweden, assignors to A B Svenska Flaktfabriken, Stockholm, Sweden

Application July 12, 1950, Serial No. 173,454
In Sweden July 12, 1949

3 Claims. (Cl. 214—8.5)

1

In producing sheet-like materials especially plates or sheets of defibrated wood, peat or similar materials a method is known by which the sheets are heated two and two with their plane surfaces in confronting engagement with each other and in this condition are introduced into a hardening chamber, where they are subjected to a heat treatment, so called hardening. The hardening is effected in order to increase the strength of the sheets and in order to affect the colour of the sheets.

The present invention relates to an arrangement for stacking and separating such sheets and similar materials and is characterised by at least one table provided with gears and a circular toothed segment by means of which the upper part of the table is rotatable about an axis common with the centre of rotation of the toothed segment. The table is provided with one or more suction ports which are connected to a suction pipe so that in a vertical position of the rotatable part of the table the sheet lying nearest to the suction ports is held against the table until the rotatable part of the table has resumed a horizontal position.

Fig. 1 is an elevational view of the invention showing the table parts in horizontal position.

Fig. 2 is a similar elevational view showing the table parts in vertical juxtaposed position.

Fig. 3 is a sectional elevational view of a table part illustrating a suction part in detail.

The sheets lying upon each other are in the drawing designated 2, 3 respectively. The sheets are fed to one or the other of a pair of tables 11 and 18 each with a rotatable upper part 10 and 19 respectively. These rotatable parts of the tables are provided with suction ports 1, 4 and 8, 9 respectively which are connected to the suction side of a fan or other suction device by means of the pipes 5, 14, 15. Each table is provided with a toothed segment 16, 13 which is driven by the gears 17, 12 respectively, whereby the table parts 10 and 19 are raised from a horizontal position to a vertical one. When separating the sheets they are first fed to one of the tables after which the rotatable parts of both tables are turned to a vertical position by means of the gear arrangement. In the embodiment shown in the drawing the rotatable parts of the tables meet in a vertical position with the sheets 2, 3 placed between the suction ports of both tables. When the table parts 11, 18 are in a vertical position or possibly during the rotation upwards the damper means of the suction pipes are opened so that the sheets 2 and 3 are held by the suction ports against the

2

table parts 10 and 19, respectively. When the table parts have obtained a vertical position, said tables turn and resume their horizontal position each table carrying with it one of the sheets which thereby is held in place by means of the suction ports. Immediately before the rotatable parts of the tables have resumed a horizontal position the dampers of the suction pipe are closed and each sheet is released from the suction ports. Thus 10 the sheets are each placed on a table separate and from there transported to succeeding treatments.

What we claim is:

1. Apparatus for stacking and separating sheet materials comprising a pair of laterally adjacent members pivotally mounted at their inner edges for swinging movement in respectively opposite directions between horizontal positions and vertical positions in which said members are disposed in closely spaced parallel relation to each other, 15 drive means for each member operable to actuate the members between said horizontal and vertical positions, means defining a plurality of suction ports in the surfaces of said members disposed in parallel confronting relation in the vertical 20 positions of the members, and a suction pipe connected to the ports of each member to hold adjacent sheets on the respective members until the same are disposed substantially in their horizontal 25 positions.

2. Apparatus for stacking and separating sheet materials comprising a pair of laterally adjacent members pivotally mounted at their inner edges for swinging movement between horizontal positions and vertical positions in which said members are disposed in closely spaced parallel relation to each other, a toothed segment fixed to each member, a drive gear meshed with each segment and operable to actuate the latter and the member between said horizontal and vertical positions, means defining a plurality of suction ports in the surfaces of said members which are disposed in parallel confronting relation in the vertical 35 positions of the members, and a suction pipe connected to the ports of each member to hold adjacent sheets on the respective members until the same are disposed substantially in their horizontal 40 positions.

3. Apparatus for stacking and separating sheet materials comprising a pair of tables arranged adjacent each other, a member pivotally mounted at the inner edge of each table for swinging movement between horizontal positions overlying the tables and vertical positions in which said members are disposed in closely spaced parallel 45 relation to each other, drive means for each member

operable to actuate the members between said horizontal and vertical positions, means defining a plurality of suction ports in the surfaces of said members which are disposed in parallel confronting relation in the vertical positions of the members, and a suction pipe connected to the ports of each member to hold adjacent sheets on the respective members until the same are disposed substantially in their horizontal positions.
